(57) **CLAIM**

The ornamental design for an electric reel for garden hoses as shown and described.

DESCRIPTION

The patent or application file contains at least one drawing executed in color. Copies of this patent or patent application publication with color drawing(s) will be provided by the Office upon request and payment of the necessary fee.

1. Electric reel for garden hoses

1.1 : Front

1.2 : Back

1.3 : Left

1.4 : Right

1.5 : Top

1.6 : Bottom

1.7 : Perspective

This design is mainly used for automatic winding and releasing of hoses; the view that shows the design point the most is the perspective view.
